UNITED STATES PATENT OFFICE.

CHARLES H. FUCHS, OF TIFFIN, OHIO.

MACHINE FOR TRIMMING BOX-CORNERS.

SPECIFICATION forming part of Letters Patent No. 468,095, dated February 2, 1892.

Application filed January 22, 1891. Serial No. 378,721. (No model.)

To all whom it may concern:

Be it known that I, CHARLES H. FUCHS, a citizen of the United States, residing at Tiffin, in the county of Seneca and State of Ohio, have invented certain new and useful Improvements in Machines for Trimming Box-Corners, of which the following is a specification, reference being had therein to the accompanying drawings.

10 This invention relates to new and useful improvements in machines for trimming the corners of wooden boxes; and it consists in the improved devices whereby the projecting ends of the tenons which join the sides of a 15 wooden box together are neatly trimmed off.

The invention further consists in the peculiar construction, arrangement, and combination of the various parts, all as more fully hereinafter described.

20 In the accompanying drawings, Figure 1 is a vertical section of my improved machine. Fig. 2 is a plan view of a portion thereof. Fig. 3 is an end elevation thereof. Fig. 4 is an end elevation of a box, showing the projecting tenons.

25 A is the frame of the machine.

B is a table supported on top.

C is a shaft journaled in suitable boxes below the table.

30 D is the pulley for revolving the shaft, and E is a revolving cutter secured to the shaft and provided around its face with oppositely-inclined knives or teeth, the cutting-edges of which are presented at right angles to each 35 other. This cutter is preferably formed of two like disks *a a*, having suitably beveled faces on which the cutting-teeth are formed. The two disks are clamped together upon the shaft so as to form a right-angled depression 40 around the face of the cutter.

G is a guide-bar supported upon the frame above the cutter and provided upon its upper face with a depression H, the sides of which are at right angles to each other and form inclined guide-faces I. A slot J is formed in the bottom of the depression and a stop K is adjustably secured in this depression. This 45 guide-bar is vertically adjustable by any suitable means, such as the screws J', which support the guide-bar at the ends, having suitable lock-nuts L to hold it in its adjusted position. If desired, the guide-bar may be con-

structed in two halves, as shown in the drawings, so as to be more conveniently manufactured, and the slot J may be enlarged 55 where the cutter is secured to form a clearance for the débris. The cutter is arranged in the longitudinal center of the guide-bar, and its cutting-edge on top forms the complementary apex of the angle of the guide-faces of said bar.

In practice, the parts being constructed and arranged as shown and described, they are intended to operate as follows: If a box joined together in the usual manner and with the 60 ends of the tenons slightly projecting at *b*, as shown in Fig. 4, is placed cornerwise into the depression H of the guide-bar, the part of the corner to be trimmed projects through the slot J, and upon pushing the box to pass over the cutter, while keeping it pressed against the guide-faces I, all the projecting ends on both sides of the corner will be trimmed off. In this manner all the corners of the box are treated. Should the cutter wear, it can be 65 sharpened by filing, which can be easily done when the two parts of the cutter are separated and the guide-bar is adjustable vertically to enable the operator to set it in proper relation to the cutter. The office of the stop 70 K is merely to tell the workman when the work is done, and it is therefore set at the proper distance away from the cutter, according to the length of the boxes to be trimmed, the guide-bar being made long enough to give 75 ample length on either side of the cutter to receive boxes of all sizes.

My improved machine trims not only both sides of a corner at once, but it has the advantage over other machines devised for the 80 purpose that the corners can in no wise be disfigured by cutting away any portion of the sides of the box.

What I claim as my invention is—

1. In a box-trimming machine, a box-corner-supporting guide and a cutter having a cutting-face corresponding to the apex of the angle of said guide and mounted to revolve therein, substantially as described.

2. In a box-trimming machine, the combination of a box-corner-supporting guide, a revolving cutter having a cutting-face corresponding to the angle of the apex of such guide and mounted to revolve therein, and

an adjustable stop secured to such guide, substantially as described.

3. In a box-trimming machine, the combination of the box-corner-supporting guide, a 5 revolving cutter having a cutting-face corresponding to the angle of the apex of such guide and mounted to revolve therein, and means for adjusting the guide to the cutter, substantially as described.
- 10 4. In a box-trimming machine, the combination, with the box-corner-supporting guide, of a revolving cutter in proximity to and

mounted to revolve in the guide formed of two disks clamped together, having inversely-beveled cutting-edges corresponding to the 15 angle of the side of the guide, substantially as described.

In testimony whereof I affix my signature in presence of two witnesses.

CHARLES H. FUCHS.
